UNITED STATES PATENT OFFICE.

ADOLF GÖBEL, FREDRICK HARNISCH, AND EMIL C. JANKE, OF BROOKLYN, NEW YORK.

HAM BOILER.

Application filed July 24, 1922. Serial No. 576,929.

To all whom it may concern:

Be it known that we, ADOLF GÖBEL, FREDRICK HARNISCH, and EMIL C. JANKE, all citizens of the United States, and residing in Brooklyn, county of Kings, State of New York, have invented certain new and useful Improvements in Ham Boilers, of which the following is a specification.

The present invention relates to an improved apparatus for holding hams or similar food articles under pressure during the process of boiling; and the principal object of the invention is the provision of a simple, inexpensive, reliable and durable apparatus for the above purpose, which can be easily and automatically operated in the quickest possible time, is easily cleaned and can be packed into a minimum of space. Various devices have been proposed having in view the compression of the ham and its automatic retention, but these have hitherto involved the use of external springs, levers and ratchets or the like which not only catch dirt and grease but take up a great deal of room thereby lessening the number of ham boilers which can be packed into a given vat at once.

We have found, moreover, that, by suppressing the use of springs for compressing the meat, a greater proportion of the liquor is preserved in the meat, thereby increasing its weight and its food value. At the same time certain features of the invention may be used either with or without springs on the cover or compressing member.

Certain preferred forms of the invention are illustrated in the accompanying drawings wherein Figure 1 is a top plan view of the complete apparatus in one form; Figure 2 is a vertical sectional view of the same on the line 2—2 in Figure 1, and Figure 3 is a partial sectional view of a modified form.

While it is, of course, possible to apply our invention to containers of almost any practicable shape, we prefer to use sheet metal containers having the general form shown in the drawings in plan and vertical section at 10. These are made of such a size as to receive each a single ham or the like; which, while lying on the bottom of the container and being confined all around, is subjected to manual pressure by means of the cover or compressing member 11.

This member preferably has the same general contour in plan as the container, and

fits it quite loosely, so as to be easily inserted over the ham and to allow free escape of steam all around it. This cover is provided with one or more catches (preferably two) which cooperate with a retaining member or members within the casing in such a manner as automatically to secure the cover in any position to which it descends. When so secured the cover resists the upward thrust caused by the resiliency or the swelling tendency of the ham.

The preferred form of apparatus comprises a double catch which is shown as formed of two flat plates 12 and 13, guided so as to slide longitudinally and toward or away from each other between the guides 14 and 15. Cross bars 16 at intervals hold these plates in constant contact with the top of the cover. The ends of the plates 12 and 13 are preferably bevelled as shown so as to form teeth which are automatically forced into the spaces between the teeth of the ratchets 17 and 18 within the end walls of the container 10. This is preferably accomplished by mounting a spiral spring 19 between the upturned ends 20 and 21 of the plates 12 and 13. A bar 22 fixed to one of these ends (as 20) extends parallel to the cover and through an opening in the other end (as 21). The spring 19 surrounds this bar and is held in place by it. A cross bar 16 on either side forms a stop against which one or the other upturned end 20, 21, is pressed by the spring, thus limiting the outward movement of the plates 12 and 13 when the cover is removed.

While the ratchet teeth 17 and 18 may be formed and applied to the container in various ways, we prefer to form opposed openings or windows in the ends of the container over which are brazed reinforcing pieces 23, 24, furnished with the teeth 17 and 18, so placed as to come opposite the windows in question.

From what has been described the operation of the device is clear. The ham having been placed in the bottom of the container, the cover is lowered upon it, preferably with one end at first lower than the other, to bring the plate, 12 or 13, at the lower end first in engagement with the corresponding ratchet. The cover is finally pressed into horizontal position over the ham, and strong pressure is exerted downward upon both ends of the cover, compressing the ham to the desired degree. As the cover descends, the tips of the plates 12 and 13 slide down

over the beveled teeth of the ratchets, springing into the successive spaces between these teeth, so that, when the operator finally ceases to press on the cover the engagement of the plates 12, 13 with the ratchet teeth will retain the cover in the position to which it had been forced. This automatic locking action continues during the entire operation of cooking the meat.

10 When the cooking is completed, and it is desired to remove the ham, the plate 13 is first released by pressing down on the right hand end of the cover (in Figure 1) while at the same time squeezing together the 15 plates 12 and 13 by pressure on their upturned ends 20, 21. The hook on the end 21 will facilitate lifting the right hand end of the cover first, and, as soon as this is accomplished, the whole cover can easily be 20 lifted out. If desired a ring 21^a may be used to assist in lifting the cover.

In Figure 3 is shown a modified form in which, instead of providing ratchet teeth at the ends, vertical rows of openings 25 are formed, into which the plates are sprung one after the other as the cover is pressed down. In this figure are also shown rollers 26 in place of the simple cross bars 16. This may be done to make the bars 12 and 13 30 move more easily. In Figure 3, also, both upturned ends 20, 21 are shown bent to facilitate lifting the cover. This figure also makes it clear that the bar 22 may, if desired, be replaced by the two opposed short 35 projections 27, 28, to hold the spring in place.

Indeed many changes may be introduced without departing from the spirit of the invention, and we do not limit ourselves to 40 the details herein shown and described.

It will be seen that our apparatus comprises a minimum of moving parts to be cleaned and kept in order, and that all of these parts are confined within the limits of 45 the container. This latter feature greatly economizes room in the boiling vat and is a valuable element of our invention.

What we claim is—

1. Apparatus of the character described comprising a container, a compressing member fitting therein, a slidably catch member at each end of the compressing member adapted to secure the same within the container, finger holds on said slidably catch members, and a single spring located between and impinging against said slidably catch members so as to tend to force them apart. 50

2. In apparatus of the character described, a container, a cover fitting into the same, two slidably mounted plates on the cover, a single spring located between and impinging against the bent ends of said plates so as to tend to force them apart, and means on the container to be engaged by the outer ends of said plates. 60

3. In apparatus of the character described, a container, a cover fitting into the same, having parallel guiding ribs, two plates slidably mounted between said ribs, 70 a spring mounted between said plates and adapted to force them apart, and means on the container to be engaged by the outer ends of said plates.

4. In apparatus of the character described, a container, a cover fitting into the same, two slidably mounted plates on said cover having their inner ends turned upward, means for guiding said plates, a spring adapted to force said plates apart, 80 and means on the container to be engaged by the outer ends of said plates. 75

5. In apparatus of the character described, a container, a cover fitting into the same, ratchet teeth inside of the container 85 at each end thereof, two slidably mounted locking plates on the cover adapted to engage said two ratchets, and a spring adapted to press said plates into locking position.

In testimony whereof we have hereto set 90 our hands on this 12th day of July, 1922.

ADOLF GÖBEL.
FREDRICK HARNISCH.
EMIL JANKE.
